WATER-COOLED HOLLOW SHAFT FOR ORE-ROASTING FURNACES.

1,173,354.

Specification of Letters Patent. Patented Feb. 29, 1916.

Application filed January 3, 1912. Serial No. 669,282.

To all whom it may concern:

Be it known that I, ERNST JENSEN-VALDAL, a subject of the King of Denmark, and resident of Copenhagen, Denmark, have invented certain new and useful Improvements in Water-Cooled Hollow Shafts for Ore-Roasting Furnaces, of which the following is a specification.

The present invention relates to a modified construction of the known water-cooled hollow-shafts with water-cooled stirring-arms which are used in mechanical furnaces for roasting pyrites and other ores.

In the previously known water cooled hollow-shafts with stirring-arms the cooling water is led in at the foot of the hollow-shaft, wherefrom it is to be distributed into all of the stirring-arms; the heated water then leaves the hollow-shaft at top; this water-cooling principle, however, is not very appropriate, because in the upper stories where most heat is developed by the burning pyrite, the arms will not be sufficiently cooled, the cooling-water received by these arms being already much heated by its streaming from below up through the hollow-shaft and through the arms in the lower stories of the furnace. Consequently an unduly great quantity of incrustation will be deposited inside the arms in the upper stories, which will further reduce the effect of the cooling water. At breaking of an arm the water will rush out into the furnace from a hole as large as the inner cross section of the arm, and the supply of water to the hollow-shaft as well as to all of the arms will have to be stopped as soon as possible, whereby there is the risk of destruction of the packings between the shaft and the arms, the temperature being here unduly quickly augmented owing to the stopping of the cooling-water; therefore the stopping of the working of the furnace and mounting of new arms instead of the broken arms often incur replacing of a couple of the other arms. Therefore the aim of the present invention has been partly a most effective cooling of the hollow shaft and of each of the arms, partly a device by which in the event of breaking of an arm it is only needed to stop the supply of water to the broken arm, and whereby it is possible, while a new arm is mounted from outside, through one of the furnace doors to con-

tinue the water-cooling of the hollow-shaft 55 proper and the other arms.

It has been attempted to attain the complete water-cooling through providing the shaft as well as each one of the arms with separate supplying pipes for water, which 60 streams to the pipes from a common water-box at top, and to provide the shaft and each single arm each with its own separate discharge-pipe, extending through the walls of the shaft so much lower than the water- 65 level in the common water-box at top as to leave the necessary difference of pressure for incurring the circulation of the cooling-water. In order to be able to regulate the quantity of cooling-water, the discharges 70 are provided with thermometers and discharge-cocks.

The inlet-pipe for the cooling-water to an arm is led to one chamber of a cast iron-box arranged in the shaft opposite to the 75 arm in question, which box by a partition-wall is divided into two compartments and which is open toward the arm, which in its longitudinal direction is divided into two chambers by means of a corresponding partition-wall; this is interrupted toward the free end of the arm, so that the cooling water may here run back through the chamber on the other side of the partition-wall in the arm and from thence farther into the 80 other compartment of the cast iron box, from whence the discharge-pipe leads the heated water farther out of the furnace.

Through the above described device it is possible in the event of breaking of an arm 90 to stop the supply of the cooling-water to the broken arm, without stopping the supply to the other arms and to the hollow-shaft. Therefore in the event of breaking of an arm the stopping of the cooling-water 95 can be limited to the arm in question, when after having stopped the furnace in order to remove the broken arm from the same, the working of the furnace can be continued, until a repair is found convenient.

In the accompanying drawing are shown 100 3 sections of a water-cooled hollow-shaft with arms according to the present invention.

In Figure 1 is shown a vertical section 105 through a hollow-shaft with two pipe-arms and inlet and discharge for the cooling-water according to the above described

system. In Fig. 2 is shown a horizontal section through the hollow-shaft with portions of two stirring arms arranged opposite to each other. In Fig. 3 is shown a 5 cross-section of an arm. Here the wall is seen which separates the two chambers of the arm. Fig. 4 shows in vertical section the roasting furnace and the cooling apparatus installed in the same.

10 In Fig. 1 A is the cooling-water-pipe which leads the water to a cooling-water-tank C which is arranged on the upper end of the hollow-shaft B, from which tank the water is distributed to the inlet-pipe D for the hollow-shaft and to the inlet-pipes for 15 the arms, of which is only shown the pipe E belonging to a single arm. The pipe D leads almost to the bottom of the hollow-shaft, from whence the water streams back up 20 through the hollow-shaft and through the discharge pipe F, which in Fig. 1 is shown on the rearmost inner side of the shaft; from the pipe F the water runs out into the ring-shaped water-vessel G, which is common 25 for all the discharges. The motion of the cooling-water down through the pipe D and up through the hollow-shaft is indicated by means of arrows. Through the pipe E and the corresponding inlet-pipes for 30 all of the other arms which are not seen in the figure, the cooling-water streams into one compartment H of the cast-iron box J, which in the figure is shown cast integral with the shaft, but may also be cast separately 35 and connected to the shaft in a known manner; from the compartment H the water runs out along one side of the partition-wall in the arm K, which is closed with a screw plug L, runs back along the other side of 40 the partition-wall, which is shown vertical in the figure, but may also have any other position; from the arm the water streams through the other compartment M of the cast iron box, which compartment with regard 45 to this arm is shown in section in Fig. 2 and with regard to the oppositely arranged arm is represented by R in Figs. 1 and 2; from the other compartment of the cast iron box the water flows through the 50 discharge pipe N which is provided with a thermometer O and a regulation-cock P, as shown in Fig. 1, out into the ring-shaped water-vessel G. A discharge pipe and its complementary regulation cock are provided 55 for compartment M. The pipes E and N are each provided with stops 8 which are

adapted to prevent water from flowing into the pipes should one of the arms K break. The motion of the water through the stirring-arms is indicated in Figs. 1 and 2 by 60 arrows.

Having now described my said invention and in what manner the same is to be performed I declare that what I claim and desire to secure by Letters Patent of 65 U. S. A. is:—

1. In a roasting furnace in combination, a hollow shaft, hollow stirring arms projecting from said shaft, individual water supplying pipes for each of said arms adapted to be closed independently of the remainder of said pipes, a water tank secured to said shaft, individual discharge pipes for each of said arms, means for regulating the flow of the water through each of said discharge pipes, and a water vessel adapted to receive the discharge from said discharge pipes, substantially as described. 70

2. In a roasting furnace, in combination, a hollow shaft, hollow stirring arms projecting from said shaft, a water tank secured to said shaft, individual water supplying pipes for said hollow shafts and for each of said arms, the pipes for each of said arms being adapted to be closed independently of the remainder of said pipes, individual discharge pipes from each of said arms and from said hollow shaft, means for regulating the flow of water through each of said discharge pipes, and a water vessel 85 adapted to receive the discharge from said discharge pipes, substantially as described. 90

3. In a roasting furnace, in combination, a hollow shaft, a tank secured to said shaft, inwardly projecting boxes within said shaft, hollow stirring arms mounted in connection with said boxes, individual water supplying pipes and water discharging pipes connected to said boxes, means for regulating the flow of water through each of said discharge 100 pipes, and means for cutting off the supply of water to each of said individual water supply pipes, and a water vessel adapted to receive the discharge from said discharge pipes, substantially as described. 105

In testimony whereof I have affixed my signature in presence of two witnesses.

ERNST JENSEN-VALDAL
